LUMINOUS ATTACHMENT FOR DOOR LOCKS

Bernard Heinz, Scranton, Pa.

Application May 28, 1951, Serial No. 228,691

4 Claims. (Cl. 250—76)

1

This invention relates to a luminous attachment for door locks.

An object of this invention is to provide an attachment which may be readily and quickly attached to a door lock whereby the keyhole for the lock will be made luminous so as to make the keyhole or barrel visible in the dark.

Another object of this invention is to provide a luminous attachment for door locks which also includes an improved key guide formed with an outer convex guiding surface to guide the key to the keyhole.

A further object of this invention is to provide an attachment of this kind which includes a base ring or element adapted to be fixedly secured as by cement or the like to the lock structure about the barrel with a luminous ring threaded or otherwise removably mounted within the base or fixed ring so that in the event the luminous material such as radium or the like carried by the latter ring becomes bad or inoperative, the removable ring may be taken from the base ring and another removable ring substituted therefor so that the barrel of the lock will be maintained visible in the dark.

A further object of this invention is to provide a luminous attachment of this kind which is so constructed that the luminous material will be diffused throughout the ring structure so that only a relatively narrow insert of the luminous material may be disposed within the removable ring.

A further object of this invention is to provide an attachment of this kind which can be readily adapted to various types and makes of locks.

With the above and other objects in view, my invention consists in the arrangement, combination and details of construction disclosed in the drawings and specification, and then more particularly pointed out in the appended claims.

In the drawings:

Figure 1 is a detailed front elevation of a luminous attachment for locks constructed according to an embodiment of this invention.

Figure 2 is a sectional view taken on the line 2—2 of Figure 1.

Figure 3 is a fragmentary sectional view taken on the line 3—3 of Figure 1.

Figure 4 is a detailed front elevation of a modified form of this invention.

Figure 5 is a sectional view of another modified form of this invention.

Figure 6 is a fragmentary sectional view taken on the line 6—6 of Figure 5.

Figure 7 is a sectional view showing another 55 modification of this invention.

2

Referring to the drawings the numeral 10 designates generally a base ring which may be formed out of plastic or other suitable composition material. The ring 10 in the present instance is secured to or formed integral with a disc-shaped plate 11 having a marginal flange 12 which is adapted to engage about a lock housing 13. The ring 10 is eccentrically disposed with respect to the plate 11 and is disposed concentrically about the lock barrel 14 which is carried by the lock housing 13.

The plate 11 is secured to the outer side of the lock housing 13 by means of cement 15. A key guiding member 16 of circular form is secured 15 as by cement 17 to the outer end of the lock barrel 14 and is provided with an annular marginal flange 18 on the inner end thereof. The key guiding member 16 is formed with a key slot 19 which conforms substantially to the key slot in 20 the barrel 14, and the guide 16 is formed with a convex inwardly tapering outer surface 20 which provides a means to guide the key toward the key hole 19.

The guide member 16 is formed with a cylindrical outer side 21 and is also provided with an annular groove 22 within which a luminous element 23 in the form of radium or the like is adapted to be seated. The key guide 16 is preferably formed out of plastic material, and by 30 forming the outer side or end of the guide member 16 with a convex surface 20 the effect of this convexity of the guide member 16 is such as to diffuse the luminosity of the radium 23 substantially throughout the body of the guide 16.

35 A removable luminous ring generally designated as 24 is removably mounted on the base ring 10 and includes an outer ring body 25 having a convex outer surface 26. The body 23 has extending from the inner end thereof a cylindrical flange 27 formed with threads 28 adapted to engage complementary threads carried by the inner side of the base ring 10.

The ring body 25 is adapted to abut against the outer end of the base ring 10 and the body 45 25 is formed with an annular groove 29 confronting the outer end of the base ring 10 within which a luminous element 30 such as radium or the like is adapted to be seated. The convexity of the outer side of the ring 25 provides a means whereby the luminosity of the radium 30 will be diffused substantially throughout the ring body 25. The inner end of the cylindrical flange 23 is adapted to confront the flange 18 carried by the guide 16 so that in the event the guide member 16 should become loose, this guide member will be held against removal or loss from the flange 27.

Referring now to Figure 4, there is disclosed a modified form of this invention wherein the ring structure 24a which is carried by the base ring 10a is mounted on a plate 31 which is of a size less than the size of the lock housing 13a. In other respects the structure shown in Figure 4 is identical with that shown in Figures 1 and 2. As shown in Figure 1 a drain hole 32 is provided in the lower portion of the base ring 10 and a similar drain hole 32a is formed in the lower portion of the base ring 10a.

In Figure 5 there is disclosed another modification of this invention wherein the base ring 33 is adapted for fixed mounting on the outer end of a cylindrical shell 34 having an inturned outer end 35. The shell 34 encompasses a lock housing 36 of a type used in certain motor vehicles, and the lock barrel 37 projects slightly from the outer end of the lock housing 36. A key guide 38 similar to the key guide 16 is fixedly secured as by cement 39 to the outer end of the lock barrel 37; and the guide 38 includes an outer annular flange 40. The base ring 33 is formed with a cylindrical flange 41 engaging about the shell 34 and secured thereto as by cement 42.

A guide retaining ring generally designated as 43 which is similar to the guide retaining or locking ring 24 is threaded into the base ring 33 as indicated at 44, and a luminous element 45 is mounted in an annular groove 46 formed in the retaining ring 43. The guide member 38 is also formed with a groove 47 in the outer cylindrical side thereof within which a luminous element 48 such as radium is adapted to be seated.

Referring now to Figure 7 there is disclosed another modification of this invention wherein the attachment is designed for mounting on the outer end of a door knob 49 having a lock barrel within which a second lock barrel 50 is rotatably mounted.

A base ring 51 similar to the ring 10 has a flared plate 52 extending therefrom which is formed with an outer annular flange 53, and the plate 52 with the flange 53 is secured to the bevelled outer side 54 of the knob by means of cement 55 or the like. A key guide 56 similar in every detail to the guide 16 is secured as by cement 57 to the outer end of the lock barrel 50, and the guide 56 which is formed with an annular outer flange 58 is retained loosely within the base ring 51 by means of a retaining ring 59 similar in every detail to the retaining ring 24.

The guide 56 has a luminous element 60 in the outer cylindrical side thereof, and the retaining ring 59 has a luminous element 61 disposed in the inner end thereof confronting the outer end of the base ring 51.

What is claimed is:

1. A luminous attachment for a lock having a lock housing and a lock barrel, said attachment comprising an annular base member adapted for fixed attachment to the lock housing, a key guide having an outer annular flange and formed with a convex outer end, a retaining ring threaded onto said base member and engaging loosely about said guide, a luminous element carried by said guide, and a luminous element carried by said ring.
- 15 2. A luminous attachment for a lock having a lock housing and a lock barrel, said attachment comprising an annular base member adapted for fixed attachment to the lock housing, a plate carried by said base member, an outer flange carried by said plate engageable about the lock housing, a key guide having an outer annular flange and formed with a convex outer end, a retaining ring threaded onto said base member and engaging loosely about said guide, a luminous element carried by said guide, and a luminous element carried by said ring.
- 20 3. A luminous attachment for a lock having a lock housing and a lock barrel, said attachment comprising an annular base member adapted for fixed attachment to the lock housing, an annular flange carried by said base member engageable about the lock housing, a key guide having an outer annular flange and formed with a convex outer end, a retaining ring threaded onto said base member and engaging loosely about said guide, a luminous element carried by said guide, and a luminous element carried by said ring.
- 25 4. A luminous attachment for a lock having a lock housing and a lock barrel, said attachment comprising an annular base member adapted for attachment to the lock housing, a key guide member within said base member, an annular flange carried by said guide member, a retaining member for said guide member, said retaining member comprising a ring having a rounded outer side, an annular flange carried by said ring threadedly engaging within said base member, and a luminous element carried by said ring.
